UNITED STATES PATENT OFFICE

ASHBY G. MURDOCK, OF PETERSBURG, VIRGINIA

CORNER BRACKET

Application filed April 8, 1931. Serial No. 528,659.

This invention relates to a corner bracket for use in connection with folding tables such as card tables, one of the objects being to provide a light but durable corner bracket 5 which will not only serve as a reinforcement for the corner of the table frame but will also constitute the sole means for connecting the pivoted leg and its brace to the table.

A further object is to provide a corner 10 bracket which can be assembled with the leg and its brace so as to form a complete leg unit which can subsequently be fastened readily to the frame of the table and insure proper relation of the leg to its brace.

With the foregoing and other objects in view which will appear as the description proceeds, the invention resides in the combination and arrangement of parts and in the details of construction hereinafter 20 described and claimed, it being understood that changes in the precise embodiment of the invention herein disclosed, may be made within the scope of what is claimed, without departing from the spirit of the invention.

In the accompanying drawing, the preferred form of the invention has been shown.

In said drawing:

Figure 1 is a bottom plan view of one corner portion of a card table to which the present improvements are applied, a portion of the leg and its brace being shown connected to the corner bracket.

Figure 2 is a section on line 2—2, Figure 1, the leg and its brace being shown extended 35 downwardly from the table.

Figure 3 is a perspective view of the corner bracket.

Referring to the figures by characters of reference, 1 designates the usual table frame 40 to which the top 2 is secured in any preferred manner, the corner portion of the frame being fastened by any means such as a corner plate 3 attached thereto.

The corner bracket constituting the present 45 invention comprises a single strip of metal bent to provide a base 4 and terminal arms 5 and 6. These arms are extended at right angles to the base 4 and the free end portion of arm 5 is offset laterally as shown at 7 so as 50 to be spaced from the frame 1 when the cor-

ner bracket is secured to the frame. The other arm 6 can be reduced in size, as shown at 8, so as to lighten the structure and both of the arms 5 and 6 are provided with apertures 9 and 10 respectively which are coaxial 55 and spaced equal distances from the base 4. The aperture 9 is in the offset portion 7 and is adapted to receive the upset end of a pivot pin 11 which extends transversely through one end portion of a leg 12. The 60 head 13 of pin 11 laps the leg and cooperates with the offset portion 7 to hold said leg against movement longitudinally of the pin.

The opening 10 holds a rivet 14 which constitutes a pivotal mounting for a diagonal 65 brace 15 one end of which, not shown, is adapted to be securely fastened to the leg as is usual in tables of this general type.

Openings 16 are formed in the base 4 and arm 5 for the reception of rivets 17 which 70 are extended through the adjacent sides of frame 1 and serve to fasten the corner bracket securely to two sides of the frame against which it will fit snugly and thus act as a reinforcement. It is preferred to so locate the 75 corner bracket that when it is secured to the frame 1 the upper edges of the base 4 and arms 5 and 6 will rest against the top 2 as shown in Figure 2.

The leg and brace can be attached to the 80 corner bracket so as to form a complete leg unit. The corner bracket can then be quickly fastened within the corner portion of the frame by means of the rivets 17 the inner 85 ends of which are adapted to be offset as shown. Thus the leg can be held properly to the table without requiring the use of an excessively long pivot pin which extends through both the leg and the frame. The leg and its brace can be assembled in proper 90 relation to each other before these parts are attached to the frame and an accurate assemblage is thus insured. The cost of connecting the parts is also reduced considerably.

What is claimed is:

The combination with a table frame, of a bracket fitted snugly in the angle of the frame and secured thereto for holding the frame together at said angle, said bracket 100

including a metal strip of uniform width bent to provide a base for attachment to one side of the frame and parallel arms formed by the end portions of the strip, separate means for attaching the base and one arm to two sides of the frame respectively, said attached arm having its free end offset inwardly from the side of the frame to which the arm is attached, separate pivot devices in said offset portion and in the other arm respectively, a leg mounted on the pivot on the offset portion and between the arms, a brace mounted on the other pivot device, said brace being attached to the leg, the bracket, leg and brace being connected together independently of the frame.

In testimony that I claim the foregoing as my own, I have hereto affixed my signature.

ASHBY G. MURDOCK.
